UNITED STATES PATENT OFFICE.

POPE COBB, OF BROWNSVILLE, TENNESSEE.

BED LOCK.

1,419,957.

Specification of Letters Patent. Patented June 20, 1922.

Application filed March 29, 1922. Serial No. 547,765.

To all whom it may concern:

Be it known that I, POPE COBB, a citizen of the United States, residing at Brownsville, in the county of Haywood and State 5 of Tennessee, have invented a new and useful Bed Lock, of which the following is a specification.

This invention aims to provide novel means for holding a bed rail on a bed post 10 in such a way that the bed rail may be reversed. Another object of the invention is to provide novel means for securely binding the rail in the socket of the bed post.

In the drawings:—

15 Figure 1 shows in plan, a device constructed in accordance with the invention, parts being broken away; Figure 2 is a side elevation; Figure 3 is a fragmental longitudinal section taken through the socket; 20 Figure 4 is a fragmental top plan showing a portion of the socket and attendant parts.

The numeral 1 marks a bed post carrying a box-like socket 2. Although the bed post 1 has been shown as being of circular cross 25 section, the socket 2 may be mounted on any kind of a bed post. The socket 2 has an opening 4 in its top and an opening 5 in its bottom, the openings being located symmetrically with respect to the axis of the 30 socket. The opening 4 preferably is somewhat larger in diameter than the opening 5.

The numeral 6 designates, generally a bed rail, the body of the bed rail comprising a first flange 7 and a second flange 8 disposed 35 at right angles to the first flange 7. A block 9 is fitted in the angle defined by the flanges 7 and 8. The block 9 is cut away to form a first flange 12 cooperating with the first flange 7 of the body of the bed rail, and to 40 form a second flange 11 cooperating with the second flange 8 of the body of the bed rail. A securing element 15 connects the flanges 7 and 12, and a securing element 14 the flanges 11 and 8, the block 9 thus being 45 held on the body of the bed rail. The block 9 has a reduced extension 16, extended into the socket 2 and completely filling the socket transversely. The flanges 7 and 8 of the rail, and the block 9 abut against 50 the inner end of the socket 2, as shown at 17. A reduced tongue 18 projects from the

part 16 of the block 9. The inner surface of the tongue 18 is supplied with a transverse groove 19 adapted to cooperate with the openings 4 and 5 in the socket 2. The 55 inner surface of the tongue 18 coincides with the axis of the socket 2, that is, in cross section, the tongue 18 is approximately one half the size of the socket 2. The groove 19 is so formed in the inner surface of the 60 tongue 18 that when a tapered pin 20 is mounted in the openings 4 and 5 of the socket and in the groove 19 of the tongue, the tongue will be moved diagonally of the 65 socket as indicated by the arrow A. The 70 result is that the end of the bed rail and the end of the block 9 are crowded against the inner end of the socket 2, and, at the same time, the tongue 18 is crowded transversely against one side of the socket, an 75 unusually tight joint resulting. Since the cross sectional area of the tongue 18 is one half the cross sectional area of the socket, the bed rail 6 may be reversed on its axis, that is, the tongue 18 may be disposed adjacent to the opposite side of the socket 2 from that shown in Figure 1.

What is claimed is:—

In a device of the class described, a bed post having a socket comprising walls; a 89 rail provided with a shoulder, and having a tongue received in the socket, the cross sectional area of the tongue being approximately one-half the cross sectional area of the socket, the tongue having a groove in 85 its inner surface, and the socket having an opening; and a retaining pin inserted into the opening and into the groove, the opening and the groove being so located with respect to each other that, when the pin is 90 inserted into the opening and into the groove, the pin will clamp the shoulder against the end of the socket and clamp the tongue against one wall of the socket.

In testimony that I claim the foregoing 95 as my own, I have hereto affixed my signature in the presence of two witnesses.

POPE COBB.
